INTRAVENOUS ATTACHMENT

Edward Eisenstein, Los Angeles, Calif.

Application February 1, 1952, Serial No. 269,511

2 Claims. (Cl. 128—214)

1

This invention relates to an intravenous attachment or to a device which will permit of a plurality of fluids being injected intravenously. It may be regarded as an improvement over the construction disclosed in United States Letters Patent No. 2,129,983, issued September 13, 1938, to J. H. Bacon.

Explanatory of the present invention, there are many instances in surgery where it is desired to introduce a plurality of fluids intravenously. For example, a glucose solution may be introduced intravenously and during the injection of the glucose solution it may be desirable to also introduce an anesthetic or whole blood, or both. It may also be desirable to discontinue the introduction of the anesthetic or the whole blood or both. In adding the anesthetic or the whole blood or discontinuing the addition of these fluids it is highly desirable that the intravenous needle which has already been injected into the vein be left undisturbed.

It is frequently highly important when an additional fluid is supplied that it reach the intravenous needle and pass therefrom into the vein very promptly.

An object of the present invention is to provide a construction wherein the additional fluid or fluids can be supplied to the conduit leading to the intravenous needle at a point very close to the intravenous needle so that a minimum amount of time is lost in transmitting the added fluid to the intravenous needle and injecting it into the vein.

Another object of the invention is to provide an attachment in the form of a tubular body adapted to be incorporated in the conduit leading to the intravenous needle at a point very close to the intravenous needle and which has a flexible laterally extending branch equipped at its entrance with a self-sealing device. The added fluid can be introduced into this branch by means of a hypodermic needle thrust through the self-sealing device and upon withdrawal of the hypodermic needle the entrance to the branch would be automatically or self-sealed. Due to the flexibility of the branch the hypodermic needle can be thrust through the self-sealing device and withdrawn therefrom without disturbing the intravenous needle which may have already been thrust into the vein. The flexibility of the branch prevents all ordinary movements of the branch occasioned by the insertion of the hypodermic needle or its withdrawal therefrom from being transmitted to the intravenous needle.

With the foregoing and other objects in view,

which will be made manifest in the following detailed description and specifically pointed out in the appended claims, reference is had to the accompanying drawings for an illustrative embodiment of the invention, wherein:

Figure 1 is a view in elevation illustrating a construction embodying the present invention under circumstances wherein only a single fluid is being supplied intravenously; and

10 Fig. 2 is a similar view, parts being broken away and shown in vertical section, illustrating the manner in which an added fluid may be supplied to the intravenous needle.

15 Referring to the accompanying drawings wherein similar reference characters designate similar parts throughout, 10 indicates an elevated source of supply or reservoir containing a liquid or fluid adapted to be supplied to the patient intravenously. This fluid may flow by gravity from the elevated reservoir through a flexible conduit 11 which may be equipped with a pinch valve 12. Usually such conduit has incorporated therein a glass or transparent drip tube 13 within which there is a nozzle from which the fluid in the container 10 may be observed to drip so that the rate at which the fluid in the container 10 is supplied to the intravenous needle 14 may be observed.

20 30 The intravenous needle 14 is illustrated as having been inserted into a vein of the patient and to have been temporarily anchored in such position such as by adhesive tape 15.

35 The attachment embodying the present invention comprises a rubber tube 16 that is open from end to end having one end applicable to the end of the conduit 11. The other end of the tubular member 16 is applicable to the intravenous needle adapter 17. In this manner the tubular body 16 can be located very close to the intravenous needle 14.

40 45 Integral with the tubular body 16 there is a flexible laterally extending branch 18 which communicates with the interior of the tubular member 16 intermediate its ends. The outer or free end of the branch 18 is enlarged and closed by a self-sealing means 19. This merely consists of a relatively large and comparatively thick body of soft rubber through which one or more hypodermic needles 20 of hypodermic syringes may be thrust.

50 55 If a glucose solution, for example, is being supplied to the patient intravenously from the reservoir 10 and it is desired to administer an anesthetic, the hypodermic syringe 21 may be filled with the anesthetic and its needle thrust

through the rubber cap 19. The anesthetic can then be forced into the branch 18 and caused to quickly flow from the branch into the intravenous needle 14 along with the glucose solution that is being supplied from the reservoir 10. It may be desirable to discontinue the administration of further anesthetic and under such circumstances the needle 20 can be withdrawn. The flexibility and compressibility of the cap 19 is such as to cause the hole formed by the needle 20 to automatically close or self-seal upon withdrawal of the needle. If it is desired to also administer an additional fluid such as, for example, whole blood, this may be supplied by replacing the syringe 21 with a syringe containing whole blood or, if desired, two syringes 21 may both have their needles 20 simultaneously thrust through the cap 19 in side by side relationship and both fluids supplied to the needle 14 in addition to the glucose solution.

It will be understood that the fluids mentioned herein are mentioned by way of explanation only and that any combination of other fluids that it is desired to administer to the patient intravenously may be employed if desired.

Due to the flexibility of the lateral branch 18 the insertion of one or more needles 20 or the withdrawal of these needles does not involve a disturbance or displacement of the needle 14. Any jerking of the branch occasioned by the insertion or withdrawal of the needles 20 is ordinarily not transmitted to the body 16 or to the needle 14.

From the above described construction it will be appreciated that by means of the improved construction the additional fluids may be supplied to the needle 14 with great rapidity, that is, with extreme promptness due to the fact that the branch 18 is located quite close to the intravenous needle 14. Furthermore, the construction is quite versatile in that additional fluids may be supplied to the patient either simultaneously or successively and discontinued as occasion may require. The insertion and withdrawal of the needles of the syringes 21 even though

these take place very close to the intravenous needle does not disturb or displace the intravenous needle. The improved construction also enables a better control to be obtained over the quantity and concentration of the liquid injected through the lateral branch.

Various changes may be made in the details of the construction without departing from the spirit and scope of the invention as defined by the appended claims.

I claim:

1. A device of the class described comprising a tubular member adapted to be incorporated in the conduit leading from a source of fluid supply to an intravenous needle adjacent the intravenous needle, said tubular member having a flexible lateral branch conduit connected through and communicating therewith intermediate its ends, and self-sealing means closing the outer end of the branch conduit enabling one or more hypodermic needles to be inserted therein to supply an additional fluid or fluids to the tubular member and upon withdrawal of the hypodermic needles to self-seal against ingress.
2. In combination, a source of fluid adapted to be injected intravenously, an intravenous needle, a conduit connecting the source of supply to the intravenous needle, a laterally extending flexible branch conduit connected to said conduit and communicating therewith adjacent the intravenous needle, and self-sealing means closing the entrance to the branch conduit enabling one or more hypodermic needles to be inserted therethrough to introduce one or more additional fluids therein and upon withdrawal of the hypodermic needles to self-seal.

EDWARD EISENSTEIN.
